UNITED STATES PATENT OFFICE.

JOHN S. NASH, OF CHICAGO, ILLINOIS.

CAP FOR SYRUP-BOTTLES AND THE LIKE.

No. 872,671.

Specification of Letters Patent.

Patented Dec. 3, 1907.

Application filed December 8, 1906. Serial No. 346,827.

To all whom it may concern:

Be it known that I, JOHN S. NASH, a citizen of the United States, and a resident of Chicago, county of Cook, and State of Illinois, have invented certain new and useful Improvements in Caps for Syrup-Bottles and the Like, of which the following is declared to be a full, clear, and exact description.

10 The invention relates to syrup bottles and the like and more particularly to syrup bottles of the kind employed at soda fountains for holding the syrups of different flavors.

The improvement seeks to provide a simple and efficient form of cap and lid for such bottles, together with operating means therefore so arranged that the neck of the bottle may be grasped and at the same time and with the same hand the lid opened.

20 The invention also seeks to provide means for arresting the lifting movement of the lid in such position that it will fall back automatically to closed position when the syrup bottle is set back in place.

25 The invention consists in the features of construction, combinations, and arrangements of parts hereinafter set forth, illustrated in the accompanying drawings and more particularly pointed out in the appended claims.

30 In the drawings, Figure 1 is a view in elevation of a syrup bottle with the improved cap applied thereto. Fig. 2 is a rear elevation of the same. Fig. 3 is a detail view in section showing the lid open.

35 The bottle 10 is provided with a neck 11 that is preferably externally screw-threaded, as shown, and provided with a flange 12 at the base of the screw-threaded portion. The 40 improved cap comprises a sleeve 13, a part 14 having a pouring lip 15, a lid 16 and operating lever 17. The sleeve 13 is preferably formed of a sheet metal tube, the lower part of which is provided with screw threads 18 to

45 engage the screw-threaded portion of the bottle neck 11. The cylindrical part 14 is preferably formed of cast metal and secured in place within the upper portion of the sleeve 13 above the screw threads 18, so as to 50 form a shoulder 19. When the cap is in position upon the neck of the bottle a flexible rubber washer 20 is preferably arranged between the shoulder 19 and the upper edge of the mouth of the bottle. The pouring lip 15 is arranged on one side of the cylindrical part 14 and is spaced from the upper edge of the

sleeve so as to form a channel 21 that catches the drip from the pouring lip and conducts it back into the bottle. The upper edge of the sleeve 13 is preferably turned in at an angle 60 to engage the part 14 about the base of the pouring lip 15.

A small plate 22 is brazed or otherwise suitably secured to the outer face of the sleeve 13 near its upper edge and at a point 65 diametrically opposite the pouring lip 15. This plate is provided with two pairs of rearwardly projecting perforated ears 23 and 24 that are arranged closely adjacent each other with one pair above the other, as shown. 70 The cup-shaped lid 16 is provided at its edge with a perforated semi-cylindrical lug 25 which fits between the upper pair of ears 23 and is secured thereto by the transverse pivot pin 26. The upper end of the operating lever 17 is arranged between the lower pair of ears 24 and is connected thereto by the transverse pivot pin 27. At its upper end and beyond the pivot pin 27 the lever 17 is provided with a curved finger 28 which 80 extends inwardly around the inside of the pivot pin 26 and, in closed position, engages the lug 25 of the lid (see Fig. 1) at a point inside of and slightly above the lid pivot 26. From the pivot 27 the lever extends downwardly closely adjacent the neck of the bottle so that, when the neck of the bottle is 85 grasped, the lever may be shifted at the same time and with the same hand inwardly toward the neck of the bottle to the position shown in Fig. 3, and the finger 28 shifted to lift the lid 16. This arrangement of the drooping or downwardly extending lever having means for opening the lid when pressed inwardly toward the neck of the bottle, provides a convenient construction and 90 enables the attendant at the soda-water fountain to grasp the neck of the bottle and at the same time—by pressing upon the lever open the lid, that is to say the lid may be 100 raised at the same time the bottle is lifted.

The lid is preferably provided at its edge above the lug 25 with a rearwardly projecting stop lug 29 that is arranged to engage a shoulder 30 on the upper end of the lever 17 105 so as to limit the lifting movement of the lid. These parts are so disposed that the lid can only open part way and cannot swing across the vertical center, the result being that, when the bottle is put back in its place, the 110 cap is automatically closed by gravity. When the lid is lifted, as shown in Fig. 3,

the curved finger 28 of the lever snugly engages the semi-cylindrical lug 25 of the lid and the latter is securely held in its raised position.

5. The improved bottle cap may be readily removed when it is desired to clean the bottle. When in position, it always insures that the bottle will be closed in spite of the carelessness of the attendant and forms a convenient construction which may be very easily manipulated as the bottle is lifted and set back in place to open and close the mouth of the bottle.

15. It is obvious that numerous changes may be made in the details set forth without departure from the essentials of the invention.

Having described my invention, what I claim as new and desire to secure by Letters Patent, is:—

20. 1. A cap for syrup bottles and the like comprising a pivoted lid, and a lever pivotally mounted adjacent the lid pivot and extending downwardly adjacent the neck of the bottle, said lever having means for lifting the lid when it is shifted inwardly, whereby the neck of the bottle may be grasped and the lid lifted simultaneously.

2. The combination with a syrup bottle or the like, of a sleeve mounted on the neck of the bottle; a lid pivoted at its edge to said sleeve and a lever pivoted to said sleeve adjacent the lid pivot and extending downwardly adjacent the neck of the bottle, said lever having means for lifting the lid when shifted inwardly, substantially as described.

3. A cap for syrup bottles and the like, comprising a sleeve, a lid pivoted at its edge to said sleeve, and a lever pivoted to said sleeve adjacent the lid-pivot, said lever having means for lifting the lid when shifted inwardly, and said lid and lever having stop portions engaging to limit the lift of said lid, substantially as described.

4. The combination with a syrup bottle or the like, of a sleeve mounted on the neck of the bottle, a lid pivoted at its edge to said sleeve and a lever pivoted to said sleeve at a point adjacent the lid-pivot, said lever having a finger extending around inside of the lid-pivot to lift the lid when the lever is shifted inwardly, said lid having a lug and said lever having a co-operating shoulder to limit the lift of the lid, substantially as described.

5. The combination with a syrup bottle or the like, of a lid therefor pivoted at its edge, and a lever pivotally mounted at a point adjacent the lid-pivot and extending down-

wardly adjacent the neck of the bottle, said lever having a finger extending around the lid-pivot and engaging the lid at a point inside of the same, whereby said lid is lifted when said lever is shifted inwardly toward the neck of the bottle, substantially as described.

6. A cap for syrup bottles or the like, comprising a sleeve, a lid pivoted at its edge to said sleeve, and a lever pivoted to said sleeve at a point adjacent and below said lid-pivot and extending downwardly therefrom, said lever having a curved finger extending around inside of the lid-pivot and engaging the lid at a point inside of and slightly above its pivot, substantially as described.

7. A removable cap for syrup bottles and the like, comprising a sleeve screw-threaded for detachably engaging the neck of the bottle, a pouring lip within and at one side of the upper portion of said sleeve, a lid and a lever pivoted to said sleeve, said lever extending downwardly from its pivot and having means for lifting the lid when shifted inwardly, substantially as described.

8. The combination with a syrup bottle or the like, of a screw-threaded sleeve detachably engaging the neck of the bottle, a pouring lip within the upper portion of said sleeve and spaced apart from the edge thereof, a lid pivoted to said sleeve and a lever for lifting the lid, substantially as described.

9. A removable cap for syrup bottles and the like, comprising a metal sleeve screw-threaded at its lower portion and having an inturned upper edge, a metal part secured within the upper portion of said sleeve and having a pouring lip at one side that is spaced apart from the edge of the sleeve, a lid and a lever pivoted at adjacent points to said sleeve, said lever having means for lifting said lid, substantially as described.

10. The combination with a syrup bottle or the like, of a metal sleeve screw-threaded to engage the neck of the bottle, a metal part secured within the upper portion of said sleeve forming a shoulder and having a pouring lip at one side, a washer interposed between said shoulder and the edge of the bottle-mouth, a lid hinged to said sleeve and means for lifting said lid, substantially as described.
